DESIGN FOR A WAFFLE IRON

James F. Faunce, Akron, Ohio, assignor to The Firestone Tire & Rubber Company, Akron, Ohio, a corporation of Ohio

Application October 4, 1940, Serial No. 95,632

Term of patent 7 years

To all whom it may concern:

Be it known that I, James F. Faunce, a citizen of the United States, residing at Akron, in the county of Summit and State of Ohio, have invented a new, original, and ornamental Design for a Waffle Iron, of which the following is a specification, reference being had to the accompanying drawing, forming a part thereof, in which:

Fig. 1 is a perspective view of a waffle iron, showing my new design;

Fig. 2 is a top plan view thereof, on a reduced scale; and

Fig. 3 is a vertical sectional view, taken on the line 3—3 of Fig. 2, in the direction of the arrows.

What is claimed is:

The ornamental design for a waffle iron, substantially as shown.

JAMES F. FAUNCE.
